UNITED STATES PATENT OFFICE.

HOWARD RENO, OF TRINIDAD, COLORADO.

DESIGN FOR A CAN-OPENER BLADE.

SPECIFICATION forming part of Design No. 25,264, dated March 24, 1896.

Application filed December 23, 1895. Serial No. 573,156. Term of patent 7 years.

To all whom it may concern:

Be it known that I, HOWARD RENO, a citizen of the United States, residing at Trinidad, in the county of Las Animas and State of Colorado, have invented and produced a new and original Design for Can-Openers; and I do declare the following to be a full, clear, and exact description of the same, reference being had to the accompanying drawing, forming a part thereof.

My invention relates to a new and original design for can-opener blades, and it will be fully understood from the following description and claim, when taken in connection with the accompanying drawing, in which the figure is a perspective view of a can-opener blade showing my design.

Referring by letter to said drawing, A indicates the can-opener blade. This blade A has a reduced shank B at its rear end and from said shank the upper and lower portions of the rear edge C of the blade diverge, as shown. The upper portion of the rear edge C merges at its upper end into the upper longitudinal edge D, which describes a convex

curve and is beveled, as illustrated, and the lower portion of said rear edge merges at its lower end into the lower longitudinal edge F, which describes a compound curve, being concave at the rear portion of the blade and 30 convex at the forward portion thereof.

The blade is reduced gradually in width and thickness from its rear edge to its forward end, and the lower longitudinal edge F extends to said forward end. The upper longitudinal edge D, however, is shorter than the lower longitudinal edge, F, and merges at its forward end into the straight and flat or non-cutting edge E, which extends to the forward end of the blade, as illustrated, the under edge of E being a cutting-edge.

What I claim is—

The design for a can-opener blade, substantially as herein shown and described.

In testimony whereof I affix my signature 45 in presence of two witnesses.

HOWARD RENO.
